UNITED STATES PATENT OFFICE.

JOHN PARNELLE FINLEY, OF TALLAHASSEE, FLORIDA.

CIGARETTE CASE.

Application filed October 17, 1925., Serial No. 63,087.

My present invention relates generally to cigarette cases, and my primary object is the provision of a small economical and convenient case adapted to receive a package 5 of cigarettes and to permit of the easy, convenient removal of one end portion of the paper cover of the cigarettes after the package has been disposed in the case, the case being so formed as to normally cover the exposed ends of the cigarette after removal, one end of the case being also constructed in such manner as to permit of ready and easy removal of the cigarette package from the case when the cigarettes have been exhausted.

In the accompanying drawing which illustrates my present invention and forms a part of this specification:

Figure 1 is a perspective view of the cigarette case as proposed by my invention showing the same closed,

Figure 2 is a vertical longitudinal section taken therethrough;

Figure 3 is a vertical transverse section, 25 and,

Figure 4 is a detailed perspective view of the blank from which the body of the case is constructed according to a modified form.

Referring now to these figures my invention proposes a cigarette case whose body 10 is of upwardly opening rectangular form, and is of a depth slightly less than the length of a cigarette package, so that when 35 a cigarette package is forced downwardly into the case, a portion of the package projects above the upper open end of the body of the case.

Obviously the body of the case may be 40 formed from seamless tubing, as contemplated in the showing in Figs. 1 to 3 inclusive, although as shown in Fig. 4, I may utilize for this purpose a blank 11 having one edge recessed at 12 and having its opposite edge recessed as at 15.

In either event the body of the case has an opening 13 in its base 14 and is provided around its upper open end with a waving shearing edge as indicated particularly at 50 16, which is preferably inturned as particularly seen in Figs. 2 and 3 in order to snugly grip the sides and ends of the cigarette package when the latter is forced downwardly into the upper open end of the case so as to rest with its lower end against the base 14.

Thus with the case in use, and with a package of cigarettes placed therein as indicated in dotted lines in Figures 2 and 3 for instance, a portion of the package extends 60 above the body of the case and especially above the inturned shearing edge 16, and the latter constitutes effective convenient means in the nature of a guide, along which a portion of the paper covering of the cigarette 65 package projecting above the edge may be torn away so as to leave the upper ends of the cigarettes exposed.

It is obvious that when the cigarette package is placed within the body 10 of the case 70 so as to rest upon the base 14, the insertion of the finger through the opening 13 in the base will enable the package to be readily forced upwardly out of the case body for instance when the cigarettes have been exhausted.

As further shown in the modification, Fig. 4, the ends of the blank are joined as by means of projecting tongues 17 at one end of the blank and conformably positioned 80 slots 18 at the opposite end thereof into and through which the tongues 17 may be pressed and crimped to form an effective lock.

In the formation of the body 10 of the case it is also preferably provided with a 85 surrounding rib 19 below its upper sharpened edge, and that portion of the case above this rib is normally covered by a cap or cover which I have shown in the nature of separable closure members 20, each hinged at 90 one edge to one side of the case as by means of hinge members embodied in the rib 19 and preferably including springs 21 whose function is to urge the separable closure members to the closed position as shown in Fig. 1, 95 at all times. These members are also preferably provided with a clasp functioning to latch the same in closed position, and which may be the usual purse latch as indicated at 22.

In use it is simply necessary to spread apart and open the separable closures 20 and then force a package of cigarettes downwardly into the case body 10 until arrested by the base 14, leaving a portion of the cigarette package in projecting relation above the upper edge of the case body. The upper exposed portion of the cover of the cigarette package is then torn away along the upper edge of the case body as a guide 105 leaving the cigarettes exposed for withdrawal in the usual manner. After the

cigarettes have been exhausted it is simply necessary to push the remaining portion of the package upwardly through the open end of the case body by the insertion of the finger 5 upwardly through the opening 13 and against the package and it is obvious from this that my invention provides a convenient cigarette case as well as one which is efficient and effective and will be economical in cost 10 and durable in use.

I claim:—

A cigarette case including a generally rectangular body shaped to receive a package of cigarettes and of a depth permitting a package 15 of cigarettes to partly protrude from the upper open end of the body when disposed therein, said body having an opening in its base, and an inwardly projecting flange around the opening, whereby to permit of 20 the introduction of a finger to facilitate dis-

charge of a cigarette package from the body after all of the cigarettes have been withdrawn and said body having an outstanding rib therearound below its upper edge, and a pair of separable similar closure members 25 adapted in the closed position to surround the upper open end of the body and the upper end of a cigarette package disposed within the body, and to engage said rib, means including hinge members housed in 30 said rib for hinging said members to the sides of the body below its upper edge, the said upper edge of the body above the hinged connections of the closure members being provided with side recesses and being slightly 35 inturned and sharpened to provide guides for the tearing of the wrapping of a cigarette package partly from the cigarettes.

JOHN PARNELLE FINLEY.
